SUPPLEMENTAL REAR GUN SIGHT

Abel E. Pierce, Wayne, Mich.

Application July 24, 1950, Serial No. 175,509

5 Claims. (Cl. 33—58)

1

This invention relates to a peep sight adapted to be associated with the conventional rear notched sight of a gun to supplement the latter and provide for quicker and easier sighting of a target.

An object of the invention is to provide a supplemental peep sight of the above kind adapted to be readily positioned and secured in operative relation to a vertically adjustable rear gun sight of the type embodying a spring leaf attached at its front end to the gun barrel and provided at its rear end with an upstanding notched sight piece.

Another object is to provide a simple and efficient supplemental sight of the above kind which is adapted to be associated with the conventional gun sight so as to provide a peep sight piece directly behind the notched sight piece of said conventional sight, as well as to underlie said notched sight piece, whereby vertical adjustment of the supplemental sight will cause corresponding adjustment of the conventional sight.

Other objects and features of the invention will appear from the following description when considered with the accompanying drawing, in which:

Figure 1 is a fragmentary side elevational view of a gun having a supplemental peep sight embodying the present invention operatively associated with the conventional notched rear sight thereof;

Figure 2 is an enlarged fragmentary view thereof, partly in side elevation and partly in central longitudinal section;

Figure 3 is an enlarged transverse section taken on the line 3—3 of Figure 1;

Figure 4 is a transverse section taken on the line 4—4 of Figure 2;

Figure 5 is a transverse section taken on the line 5—5 of Figure 2;

Figure 6 is a view similar to Figure 5, showing the supplemental sight adjusted upwardly; and,

Figure 7 is an enlarged perspective view of the supplemental sight, per se.

Referring in detail to the drawing, 5 indicates a gun barrel equipped with a conventional vertically adjustable rear sight of the type generally disclosed in the U. S. patent to C. A. Nelson, No. 1,464,615, August 14, 1923, with the elevator or wedge adjusting member omitted or removed. This conventional sight includes a spring leaf 6 having its front end attached at 7 to the barrel 5 and provided at its rear end with an upstanding notched sight piece 8 whose sides project beyond the sides of the leaf 6 to provide bottom

2

shoulders 9. The leaf 6 has a central longitudinal slot 10 in its rear portion to receive the usual notched elevator or wedge member (not shown) by means of which the sight piece 8 is ordinarily adjusted vertically.

The illustrated embodiment of the present supplemental sight includes a sight piece composed of a base block 11 having a longitudinal groove 12 of arcuate cross-section in the top thereof and 10 provided at the back with an integral upstanding plate member 13 having a peep hole 14 whose lower portion coincides with the groove 12. Spaced parallel legs 15 are integral with and project forwardly from the bottom of the block 11, and transverse notches 16 are provided in tops of the rear ends of the legs 15. The forward ends of the legs 15 are connected by a bridge member 17 in the form of a substantially C-shaped clip having its ends tightly clinched under said legs and formed intermediate its ends and between said legs with a depressed teat 18. The block 11 has a vertical central threaded opening 19 therethrough in which is screwed an adjusting screw 20.

25 The supplemental sight is installed by sliding the legs 15 forwardly under the sight piece 8 until the shoulders 9 of the latter seat in the notches 16 of legs 15 and the block 11 abuts the rear side of said sight piece 8, the spring leaf 6 being snugly received between said legs 15 and the block 11 being seated upon the barrel 5 between the sight piece 8 and the breech 21 of the gun. The clip 17 is then applied so that the leaf 6 is held thereby between the front end portions of the legs 15, the teat 18 projecting into the slot 10 of leaf 6. By threading the screw 20 downwardly, it engages the barrel 5 and jacks the block 11 upwardly to flex the leaf 6 and adjust the sight piece of the auxiliary sight upwardly, as well as to correspondingly adjust the notched sight piece 8. By turning the screw 20 in a reverse direction, the sight pieces are allowed to lower under the action of the spring leaf 6. The lowering of the sight pieces is partly limited by engagement of the ends of clip 17 with the barrel 5. The plate 13 of the peep sight piece is close to the sight piece 8, and the groove 12 and hole 14 are registered with the notch of said sight piece 8. Thus, the sight pieces are jointly used to promote easier and quicker sighting of a target.

What is claimed as new is:

1. In combination with a gun barrel, and a conventional notched rear sight including a spring leaf attached at its front end to said barrel and having an upstanding notched sight piece

at its rear end, a supplemental sight including a peep sight piece having a peep hole alined with the notch of said notched sight piece and disposed behind and abutting the latter, and spaced parallel legs rigid with and projecting forwardly from the peep sight piece under said notched sight piece and at opposite sides of said spring leaf.

2. In combination with a gun barrel, and a conventional notched rear sight including a spring leaf attached at its front end to said barrel and having an upstanding notched sight piece at its rear end, a supplemental sight including a peep sight piece having a peep hole alined with the notch of said notched sight piece and disposed behind and abutting the latter, and spaced parallel legs rigid with and projecting forwardly from the peep sight piece under said notched sight piece and at opposite sides of said spring leaf, said legs having notches in which the notched sight piece is seated, and means carried by said peep sight piece for vertically adjusting the latter and the notched sight piece.

3. In combination with a gun barrel, and a conventional notched rear sight including a spring leaf attached at its front end to said barrel and having an upstanding notched sight piece at its rear end, a supplemental sight including a peep sight piece having a peep hole alined with the notch of said notched sight piece and disposed behind and abutting the latter, and spaced parallel legs rigid with and projecting forwardly from the peep sight piece under said notched sight piece and at opposite sides of said spring leaf, and a bridge member connecting the front ends of said legs and overlying said spring leaf.

4. In combination with a gun barrel, and a conventional notched rear sight including a spring leaf attached at its front end to said barrel and having an upstanding notched sight piece at its rear end, a supplemental sight including a peep sight piece having a peep hole alined with the notch of said notched sight piece and disposed behind and abutting the latter, and spaced parallel legs rigid with and projecting forwardly from the peep sight piece under said notched sight piece and at opposite sides of said spring leaf, and a bridge member connecting the front ends of said legs and overlying said spring leaf, said spring leaf having a longitudinal slot, said bridge member having a depressed seat engaged in said slot.

5. In combination with a gun barrel, and a conventional notched rear sight including a spring leaf attached at its front end to said barrel and having an upstanding notched sight piece at its rear end, a supplemental sight including a peep sight piece having a peep hole alined with the notch of said notched sight piece and disposed behind and abutting the latter, and spaced parallel legs rigid with and projecting forwardly from the peep sight piece under said notched sight piece and at opposite sides of said spring leaf, said peep sight piece comprising a block having a longitudinal groove of arcuate cross-section in the top thereof and provided at the back with an upstanding plate member formed with said peep hole, said groove coinciding with the lower portion of said peep hole.
